US0D1068924S

(12) **United States Design Patent** (10) **Patent No.:** **US D1,068,924 S**
(45) **Date of Patent:** **** Apr. 1, 2025**

(54) **DIGITAL SIGNAGE**

(71) Applicant: **LG ELECTRONICS INC.**, Seoul (KR)

(72) Inventors: **Youngwoo Kim**, Seoul (KR); **Seungdon Lee**, Seoul (KR); **Hongyoul Choi**, Seoul (KR)

(73) Assignee: **LG ELECTRONICS INC.**, Seoul (KR)

(**) Term: **15 Years**

(21) Appl. No.: **35/520,524**

(22) Filed: **Apr. 6, 2023**

(80) **Hague Agreement Data**

Int. Filing Date: **Apr. 6, 2023**

Int. Reg. No.: **DM/228386**

Int. Reg. Date: **Apr. 6, 2023**

Int. Reg. Pub. Date: **Apr. 12, 2024**

(30) **Foreign Application Priority Data**

Nov. 17, 2022 (KR) 30-2022-0047686

(51) **LOC (15) Cl.** **20-03**

(52) **U.S. Cl.**

USPC **D20/39; D14/129**

(58) **Field of Classification Search**

USPC D14/126, 239, 129, 451, 374, 375; D20/19, 10, 42, 41, 39

(57) **CLAIM**

The ornamental design for digital signage as shown and described.

DESCRIPTION

1. Digital signage

1.1 : Perspective

1.2: Rear perspective view

1.3 : Front

1.4 : Back

1.5 : Left

1.6 : Right

1.7 : Top

1.8 : Bottom

1.9 : Perspective

1.10: Rear perspective view

1.11 : Front

1.12 : Back

1.13 : Left

1.14 : Right

1.15 : Top

1.16 : Bottom

1.17 : Perspective

1.18: Rear perspective view

1.19 : Front

1.20 : Back

1.21 : Left

1.22 : Right

1.23 : Top

1.24 : Bottom

(Continued)

The broken lines indicate portions of the article that form no part of the claimed design; reproduction 1.1 to 1.8 show the claimed design in a first position; reproduction 1.9 to 1.16 show the claimed design in an alternate position; reproduction 1.17 to 1.24 show the claimed design in another alternate position.

1 Claim, 24 Drawing Sheets
